BUNG RING CONSTRUCTION

Charles H. Draper, Cleveland Heights, and Walter C. Grosser, Cleveland, Ohio, assignors to The Draper Manufacturing Company, Cleveland, Ohio, a corporation of Ohio

Application January 4, 1935, Serial No. 320

14 Claims. (Cl. 285—49)

The invention relates to bung ring construction for metallic containers, barrels, drums, vessels, packages and the like, utilized for shipping, storing and/or dispensing fluid, liquid, or semi-solid materials; and relates more particularly to the rigid attachment of a relatively heavy or massive metallic bung ring, having a relatively large opening therethrough, to a thin sheet metal wall of a metallic container without welding or 10 seaming.

Metallic containers are extensively used for transporting, storing and dispensing various kinds of oils, lubricants and the like; and it is frequently desirable, if not necessary, to provide such containers with bung rings having large openings for ready access to such contained materials when they have high viscosity. It is likewise desirable, if not necessary, to provide such containers with bung rings having large openings for the reception and attachment of any one of a number of different types of dispensing pumps when the contained materials are relatively fluid.

In such instances, it may also be required that the bung ring be provided with external threads located outwardly with respect to the container wall to which the bung ring is attached. Moreover, it may frequently be required that the bung ring be accurately located in a certain particular or predetermined position with respect to the container wall to which it is attached. And finally, it may sometimes be required that the bung ring be a die-cast metal bung ring.

Under such conditions, it may be impossible to satisfactorily attach a relatively large and massive bung ring to a thin sheet metal container wall by seaming or welding, which constitute the usual modes of attachment of bung rings to metallic container walls.

Thus, the welding of a heavy metal bung ring to a thin metal container wall may so weaken the thin sheet metal wall adjacent to the bung ring that the resulting container is imperfect. Moreover, when welding is utilized, bung rings cannot always be accurately located in a predetermined position with respect to the container wall.

Likewise, when a seam is used for attaching a bung ring to a container wall, a gasket seal is almost always provided between the container wall per se and the closure means for the bung ring in order to make the joint between the bung ring and container wall leak proof; and such a gasket seal cannot ordinarily be provided when 55 a bung ring having an annular externally thread-

ed portion projecting outwardly from a container wall is utilized.

These problems are further complicated by the fact that the bung ring must be so rigidly secured to the container wall that the bung ring will not turn or rotate with respect to the container wall when twisting forces are applied to the bung ring, or to a member being screwed onto or unscrewed from the bung ring; because a turning or rotation of the bung ring in the container wall would so loosen the joint between the bung ring and container wall that leakage might occur.

It is therefore an object of the present invention to provide a bung ring construction for a metallic container in which a relatively heavy or massive metallic bung ring having a relatively large opening therethrough is attached by a leak-proof joint to a thin sheet metal wall of a metallic container without welding or seaming.

A further object of the present invention is to provide for the attachment of a bung ring having an annular outwardly projecting externally threaded portion, to a thin sheet metal container wall.

A further object of the present invention is to provide for the attachment of a bung ring to a metallic container wall whereby the bung ring may always be accurately located in a certain predetermined position with respect to the container wall.

Moreover, it is an object of the present invention to provide a bung ring construction for a metallic container in which a die cast metal bung ring is rigidly attached in a leak-proof manner to a thin sheet metal container wall.

It is likewise an object of the present invention to provide a bung ring construction for a metallic container in which a bung ring is attached to a thin sheet metal wall of the container, and in which axial withdrawal of the bung ring from the opening in the container wall within which the bung ring is located, is prevented.

It is also a further object of the present invention to provide a bung ring construction for a metallic container in which a bung ring is attached to a thin sheet metal wall of the container, and in which rotation or turning of the bung ring in the opening in the container wall within which the bung ring is located, is prevented.

Moreover, it is a further object of the present invention to provide a bung ring construction for a metallic container in which a bung ring is attached to a container wall, and in which

55

- registering means are provided on the bung ring and container wall for accurately positioning the bung ring in the opening in the container wall within which the bung ring is located.
- 5 And finally, it is an object of the present invention to provide a simplified bung ring construction for a metallic container having a low manufacturing cost and which incorporates the aforesaid desiderata.
- 10 These and other objects may be obtained by the elements, parts, combinations and constructions constituting the present invention, preferred embodiments of which are shown in the accompanying drawings and are hereinafter described in detail and claimed, which may be stated in general terms as including in bung ring construction for a metallic container, a thin sheet metal container wall provided with a preferably integral tubular neck forming a bung opening for the container projecting or extending preferably inwardly of the container from the wall, the neck terminating in an inturned annular flange or lip, the lip having one or more pairs of projecting lugs forming locating means, a heavy metallic bung ring having an annular sleeve portion provided with an outer peripheral surface frictionally engaging the inner peripheral surface of said neck, there preferably being an annular shoulder on said annular sleeve portion adjacent to the inner end thereof normally resting on said lip, there being one or more projecting ears on said sleeve portion below and spaced from said shoulder engaging under said lip, said bung ring being provided with an annular externally threaded flange at its upper end lapping said neck and container wall exteriorly thereof, a sealing gasket interposed between the container wall and the bung ring flange, one of said ears being located and engaged between the lugs of one of said pairs of lugs, preferably a heavy metallic ring pressed onto said neck rigidly clamping the neck between the heavy ring and bung ring sleeve, and rivet or pinning means securing said heavy ring, neck and bung ring sleeve together.
- 15 In the accompanying drawings, which show the present improvements:—
- Figure 1 is a side elevation of a container partly broken away to show the improved bung ring construction;
- 20 Fig. 2 is an enlarged sectional view of the bung ring construction shown in Fig. 1;
- 25 Fig. 3 is a top plan view of the parts shown in Fig. 2;
- 30 Fig. 4 is a bottom plan view of the improved bung ring construction shown in Fig. 2, certain parts being in section as on the line 4—4, Fig. 2;
- 35 Fig. 5 is an enlarged view of a portion of Fig. 2;
- 40 Fig. 6 is a fragmentary elevation of certain of the parts shown in Fig. 5, looking from the line 6—6, Fig. 5;
- 45 Fig. 7 is an enlarged view of another portion of Fig. 2;
- 50 Fig. 8 is a view similar to Fig. 7 showing a modified form of construction;
- 55 Fig. 9 is a sectional view of a screw cap which may be used as a closure for the bung ring shown in Figs. 1 and 2;
- 60 Fig. 10 is a sectional view of the bung ring shown in Figs. 1 and 2 prior to insertion in the bung opening of a container wall;
- 65 Fig. 11 is a bottom plan view of the bung ring shown in Fig. 10 looking in the direction of the arrows 11—11, Fig. 10;
- 70 Fig. 12 is a fragmentary sectional view of a

portion of a container wall showing the bung opening therein prior to assembling a bung ring in the opening;

Fig. 13 is a bottom plan view of the parts shown in Fig. 12 looking in the direction of the arrows 13—13, Fig. 12;

Fig. 14 is a sectional view of a ring utilized in securing the bung ring to the container wall;

Fig. 15 is a bottom plan view of the ring shown in Fig. 14 looking in the direction of the arrows 15—15, Fig. 14; and

Fig. 16 is a fragmentary sectional view showing one step in a preferred manner of securing the bung ring to the neck and reenforcing ring.

Similar numerals of reference indicate corresponding parts throughout the various figures of the drawings.

A wall of a metallic container or vessel 17 of any well known type is generally indicated at 18 (Fig. 1), and the same is preferably the top head 20 of the container and may be seamed in the usual manner at 19 to the container side wall 20. The wall 18 is made of relatively thin sheet metal and is provided with a preferably integral tubular neck 21 (Fig. 12), which projects preferably inwardly of the container and terminates in an inturned annular flange or locking lip 22, to form a bung opening for the container; and the container wall 18 is preferably reinforced against distortion at and adjacent to the opening by providing the annular shoulder 23 around the opening.

The juncture between the neck 21 and the wall 18 is preferably formed with a rounded raised bead 24 for a purpose which will be hereinafter described. The locking lip 22 is preferably provided with a pair of lugs 25 (Fig. 13) initially projecting inwardly from the locking lip 22 for a purpose which will also be hereinafter described.

The bung ring to be secured to the wall 18 is generally indicated at 26 (Fig. 10) and, referring to Fig. 1, the same has a relatively large opening therethrough as compared with the size of the container head; and the bung ring 26 is likewise relatively massive and heavy, as compared with the thin sheet metal from which the walls 18 and 20 of the container 17 are formed.

The bung ring 26 (Fig. 10) includes an annular sleeve portion 27 provided with an outer peripheral surface 28 which terminates in an annular shoulder 29, adjacent to the lower or inner end 30 thereof. The bung ring sleeve 28 is also provided with a plurality of projecting ears 31, also adjacent to the inner end 30 thereof and spaced from and below the shoulder 29.

The bung ring 26 is likewise provided at its upper or outer end with an annular flange 32, which is externally threaded at 33; and the annular flange 32 is formed with an annular shoulder 34 at the upper end of the sleeve portion 27. The bung ring 26 may be a casting, forging or a pressed metal part; and in the embodiment illustrated in the drawings, the same may preferably be a die casting.

Referring to Figs. 2, 10 and 12, the bung ring 26 is assembled with and secured to the container wall 18 by inserting and telescoping the same within the tubular neck 21 to the position shown in Fig. 2 of the drawings whereby the outer peripheral surface 28 of the bung ring frictionally engages the inner peripheral surface 35 of the tubular neck 21, a gasket 36 being interposed between the bung ring shoulder 34 and the rounded bead 24 at the upper end of the neck for providing

ing a liquid tight seal between the bung ring and the container wall.

The bung ring 26 is assembled to the container wall 18 before the container wall 18 has been seamed to the container wall 20; and as the bung ring 26 is pressed into the tubular neck 21, the ears 31 ride over or slip past the locking lip 22 and engage under the lip to prevent axial removal of the bung ring from the neck 21. When the ears 31 are engaged below the lip 22, the gasket 36 is compressed between the bung ring shoulder 34 and the rounded container wall bead 24, which is overlapped by the bung ring flange 32.

In this position of the parts (Fig. 2), the bung ring shoulder 29 preferably contacts, engages or rests on the lip 22; although it is not necessary for the shoulder 29 to seat on the lip 22 in order to effect a seal, because the seal is provided by the frictional engagement between the surface 28 and 33, and by the gasket 34. On the contrary, the parts must be so proportioned that the gasket 34 is tightly pinched or compressed before the shoulder 29 seats on the lip 22.

The ears 31 serve another purpose, that is, they may be used as a means of accurately locating the bung ring at a certain predetermined position with respect to the container wall; and this is accomplished by inserting the bung ring 26 into the tubular neck 21 in such a manner that one of the ears 31 interengages between the two lugs 25 of the pair of lugs shown in Fig. 13. As the engaged ear 31 rides over the lip 22, the ears 25 become bent downwardly as shown at 25a in Figs. 2, 4, 5 and 6, thus accurately locating the bung ring in the tubular neck 21. The lugs 25a likewise serve, by engaging the lug 31 at each end 31a thereof, to normally prevent rotation of the bung ring in the tubular neck 21.

While only one pair of lugs 25 are shown in the drawings, it is to be understood that a pair of lugs may readily be provided on the lip 22 for each locking ear 31 with which the bung ring 26 is provided.

The bung ring 26 may be closed in any suitable manner as by any usual form of screw cap such as the octagonally headed cap 37 best shown in Figs. 2, 3 and 9. The cap 37 is screwed onto the threaded bung ring flange 32 and may be sealed in liquid-tight sealing relation thereto by the sealing gasket 38.

Although the interengagement between the lugs 25a and ear 31 (Fig. 6) normally holds the bung ring 26 against rotation in the tubular neck 21, yet if a severe twisting force is transmitted to the bung ring, as for instance when the cap 37 is being tightly screwed onto the bung ring, the strength of the lugs 25a and the ear 31 is not sufficient to prevent rotation of the bung ring, because either the lugs or the ear or both may be sheared off.

Accordingly, after the bung ring 26 has been pressed into the tubular neck 21, a relatively heavy metallic ring 39 (Fig. 14) is pressed over the neck 21 so that the neck 21 is rigidly clamped between the bung ring sleeve 27 and the ring 39, and is reinforced thereby. The ring 39 is preferably formed with three holes as shown at 42, Figs. 14 and 15.

After the ring 39 is so positioned (Figs. 2 and 4), the neck 21 and bung ring sleeve 27 may be drilled at 40 to receive preferably drive screw rivets 41, which secure the ring 39, the neck 21 and the bung ring 26 together. The drilling of the holes 40 is preferably accomplished by drilling through the

holes 42 previously provided in the ring 39, as shown in Fig. 16.

If it is unnecessary to accurately locate the bung ring 26, the lugs 25 may be dispensed with because the rivets 41 and ring 39 securely clamp 5 and hold the bung ring against rotation within the neck 21.

In certain cases, it may be unnecessary to provide the additional ring 39, and in such event the tubular neck 21 and bung ring sleeve 27 may be 10 riveted together to hold the bung ring against rotation.

Referring to Fig. 8, the use of drive screw rivets 41 is not essential, but ordinary rivets 41a may be utilized for securing the bung ring sleeve 27, 15 the tubular neck 21 and the ring 39 together. Likewise, referring to Fig. 8, the upper end of the ring 39 may be rounded at 43 to fit into the rounded head 24 provided at the juncture between the neck 21 and wall 18 for reinforcing the bead 20 24 and insuring a tight seal with the gasket 36.

The improved bung ring construction fully lends itself to all requirements and uses for metallic containers during shipping, storing and dispensing, and provides a simplified and inexpensive 25 construction by which relatively heavy metallic bung rings having relatively large openings therethrough may be rigidly attached to and accurately located with respect to a thin sheet metal container wall without welding or seaming, so as to 30 provide a bung ring flange projecting outwardly from the container which may be externally threaded if desired.

The above description and the drawings referred to therein, are illustrative of structures 35 embodying our invention, and the claims appended hereto are intended to cover such modifications of and slight changes in the structures shown and described, as are apparent to those skilled in the art. 40

We claim:—

1. In bung ring construction for a metallic container, a wall provided with a tubular neck projecting inwardly therefrom forming a bung opening, a bung ring having a sleeve telescoped within said neck, the bung ring being provided at its outer end with a flange lapping said neck and container wall, means preventing the bung ring from being withdrawn from the neck, and separate means extending through the bung ring sleeve and neck securing the bung ring against rotation in the neck.

2. In bung ring construction for a metallic container, a wall provided with a tubular neck projecting inwardly therefrom forming a bung opening, a bung ring having a sleeve telescoped within said neck, the bung ring being provided at its outer end with a flange lapping said neck and container wall, a gasket interposed between said flange and container wall, means preventing the bung ring from being withdrawn from the neck and holding the gasket under compression, and separate means extending through the bung ring sleeve and neck securing the bung ring against rotation in the neck. 65

3. In bung ring construction for a metallic container, a wall provided with a tubular neck projecting therefrom forming a bung opening, the neck terminating in an inturned lip, a bung ring having a sleeve telescoped within said neck, the 70 bung ring being provided at its outer end with a flange lapping said neck and container wall, means projecting outwardly from the bung ring slipping past and engaged under said inturned lip preventing the bung ring from being with- 75

drawn from the neck, and means securing the bung ring against rotation in the neck.

4. In bung ring construction for a metallic container, a wall provided with a tubular neck projecting therefrom forming a bung opening, the neck terminating in an inturned lip, a bung ring having a sleeve telescoped within said neck, the bung ring being provided at its outer end with an externally threaded flange lapping said neck and container wall, an ear projecting outwardly from the inner end of said bung ring sleeve slipped past and engaged under said inturned lip, and means securing the bung ring against rotation in the neck.

5. In bung ring construction for a metallic container, a wall provided with a tubular neck projecting inwardly therefrom forming a bung opening, a bung ring having a sleeve telescoped into and frictionally engaged within said neck, means providing a compressed liquid-tight seal between said bung ring and container wall, and separate means extending through the bung ring sleeve and neck securing the bung ring against rotation in the neck.

6. In bung ring construction for a metallic container, a wall provided with a tubular neck projecting therefrom forming a bung opening, a bung ring having a sleeve telescoped within said neck, a ring telescoped over said neck clamping the neck against said bung ring sleeve, means providing a compressed liquid-tight seal between said bung ring and container wall, and means extending through the telescoped ring, neck and bung ring sleeve securing the said telescoped ring, neck and bung ring sleeve together.

7. In bung ring construction for a metallic container, a wall provided with a tubular neck projecting therefrom forming a bung opening, the neck terminating in an inturned lip, a bung ring having a sleeve telescoped within said neck, the bung ring being provided at its outer end with a flange lapping said neck and container wall, an ear projecting outwardly from the inner end of said bung ring sleeve slipped past and engaged under said inturned lip, and inturned lugs on said lip bent downward as the sleeve is telescoped within said neck engaging said ear holding the bung ring against rotation in the neck.

8. In bung ring construction for a metallic container, a wall provided with a tubular neck projecting therefrom forming a bung opening, the neck terminating in an inturned lip, a bung ring having a sleeve telescoped within said neck, the bung ring being provided at its outer end with a flange lapping said neck and container wall, an ear projecting outwardly from the inner end of said bung ring sleeve slipped past and engaged under said inturned lip, and rivet means extending through the bung ring sleeve and neck securing the neck and bung ring sleeve together.

9. In bung ring construction for a metallic container, a wall provided with a tubular neck projecting therefrom forming a bung opening, the neck terminating in an inturned lip, a bung ring having a sleeve telescoped within said neck, the bung ring being provided at its outer end with a flange lapping said neck and container wall, an ear projecting outwardly from the inner end of

said bung ring sleeve slipped past and engaged under said inturned lip, inturned lugs on said lip bent downward as the sleeve is telescoped within said neck engaging said ear for locating the bung ring in said neck, and rivet means extending through the bung ring sleeve and neck securing the bung ring and neck together.

10. In bung ring construction for a metallic container, a wall provided with a tubular neck projecting therefrom forming a bung opening, a cast metal bung ring having a sleeve telescoped within said neck, the bung ring being provided at its outer end with an externally threaded flange lapping said neck and container wall, and means securing the bung ring against rotation in the neck.

11. In bung ring construction for a metallic container, a wall provided with a bung opening, a cast metal bung ring in said bung opening provided at its outer end with an externally threaded flange lapping said container wall, means providing a compressed liquid-tight seal between said bung ring and container wall, and means securing the bung ring against rotation in the opening.

12. In bung ring construction for a metallic container, a wall provided with a tubular neck projecting therefrom forming a bung opening, the neck terminating in an inturned lip, a bung ring having a sleeve telescoped within said neck, a ring telescoped over said neck clamping the neck against said bung ring sleeve, means projecting outwardly from the bung ring engaging under said inturned lip preventing the bung ring from being withdrawn from the neck, and means extending through the telescoped ring, neck and bung ring sleeve securing the said telescoped ring, neck and bung ring sleeve together.

13. In bung ring construction for a metallic container, a wall provided with a tubular neck projecting therefrom forming a bung opening, the neck terminating in an inturned lip, a bung ring having a sleeve telescoped within said neck, a ring telescoped over said neck clamping the neck against said bung ring sleeve, and means projecting outwardly from the bung ring slipped past and engaged under said inturned lip preventing the bung ring from being withdrawn from the neck.

14. In bung ring construction for a metallic container, a wall provided with a tubular neck projecting therefrom forming a bung opening, the neck terminating in an inturned lip, a bung ring having a sleeve telescoped within said neck, the bung ring being provided at its outer end with an externally threaded flange lapping said neck and container wall, a ring telescoped over said neck clamping the neck against said bung ring sleeve, a gasket interposed between said flange and container wall, an ear on the inner end of said bung ring sleeve engaging under said lip and holding the gasket under compression, lugs on said lip engaging said ear for locating the bung ring in said neck, and rivet means securing the said telescoped ring, neck and bung ring sleeve together.

CHARLES H. DRAPER.
WALTER C. GROSSE.
